UNITED STATES PATENT OFFICE.

DON HENRY KENT, OF URBANA, OHIO, ASSIGNOR, BY DIRECT AND MESNE ASSIGNMENTS, TO THE AMERICAN AUTOMATIC LIGHT COMPANY, OF URBANA, OHIO, A CORPORATION OF OHIO.

AUTOMATIC GAS-REGULATOR.

No. 806,474.

Specification of Letters Patent.

Patented Dec. 5, 1905.

Application filed April 3, 1905. Serial No. 253,607.

To all whom it may concern:

Be it known that I, DON HENRY KENT, a citizen of the United States, residing at Urbana, in the county of Champaign and State of Ohio, 5 have invented certain new and useful Improvements in Automatic Gas-Regulators, of which the following is a specification.

My invention relates to improvements in automatic gas-regulators for gas-burners, and 10 particularly for incandescent burners, in which the intensity of the light and the life of the incandescent mantle depend upon the accurate regulation of the gas-supply.

My invention has for its object the automatic control of the gas-supply to the work 15 to be performed, thus effecting a saving both in the gas and in the incandescent mantles, as well as securing a more perfect and efficient light. I attain this object by the construction 20 shown in the accompanying drawings, in which—

Figure 1 is a side elevation of a gas-burner to which my invention has been applied. Fig. 2 is a detail view of that part of the burner 25 where the valve is located, and Fig. 3 is a detail view of the valve and valve connections.

Like parts are represented by similar letters of reference throughout the several views.

30 In the accompanying drawings I have shown my device attached to and operating in connection with a simple form of incandescent burner; but it is obvious that it may be employed with the various forms of burners now 35 in use. In said drawings, *a* represents the burner, which in this case is of the usual Bunson type and provided with an incandescent mantle *a'*, supported in the usual way to receive the heat which renders the same in- 40 candescent. *a'* is a gas-conduit leading there- to. Located within the conduit is a valve *b*, preferably conical in shape and adapted to open or close an opening *b'*, which leads to the burner proper—in this case through the 45 mixing-chamber *a''*, where the proper mixture of air and gas is formed. This valve is supported on the end of a valve-lever *b''*, which is mounted on a projecting arm *b'''*, attached to a suitable part of the supporting-frame of 50 the burner proper. The arm *b'''* is preferably perforated at its outer end to receive the end of a thermostatic rod *c*. It is also provided with a spring *b'* of suitable construction to

close the valve. This rod is supported at its upper end on a suitable support *c'* adjacent to 55 the burner proper or in position to receive the heat therefrom. It is screw-threaded at its lower end and provided with a regulating-screw *c''*.

The support *c'* is preferably offset, as 60 shown, so as to be farther removed from the action of the heat of the burner, and it is preferably formed of a material having less expansion by changes of temperature than the thermostatic rod *c*. 65

In operation the gas is supplied to the burner through the usual key, which may be opened to the fullest extent and the burner ignited. The valve is adjusted by turning the nut *c''* until with a normal pressure the valved opening *b'* will permit a sufficient amount of gas to pass through to supply the light or heat desired at the burner. In the event that the gas-pressure should be increased for any cause a greater amount of gas will be supplied, which 75 will force the heat products in contact with the thermostatic rod *c* and cause the same to expand and permit the valve to close through the operation of a spring *b'*. In the event that the pressure is reduced or for any reason 80 the supply of gas to produce the normal temperature is cut off the rod will retract and open the valve.

It will be seen that the construction is extremely simple and has proven sufficient for 85 automatically regulating the supply of gas to retain the burner in normal position under the various fluctuations which may occur in the gas-pressure, thus producing not only a better light, but also effecting a saving of the gas 90 and causing the burners to operate with greater efficiency. It is especially efficient and valuable in the saving of the mantles of incandescent burners, the life of which depends upon the proper regulation of the gas-supply, an 95 abnormally high pressure of gas causing the mantles to break and an abnormally low pressure causing them to become carbonized, which destroys their efficiency for light as well as their life. 100

Having thus described my invention, I claim—

1. The combination with a gas-burner, an incandescent mantle surrounding said burner, a conduit leading to said burner, a valve for 105 said conduit, a thermostatic rod arranged in

proximity to said mantle and supported stationarily at one end, and at the other end attached to said valve, said rod being adapted by its elongation and contraction to control 5 the position of said valve and the flow of gas to said burner, substantially as and for the purpose specified.

2. The combination with a burner and its mantle, a conduit leading to said burner, a valve in said conduit, a pivoted lever connected to said valve, a thermostatic rod supported adjacent to said mantle and connected to said lever, a spring attached to said lever adapted to close said valve, and an adjustable connection 10 between said rod and lever, substantially as and for the purpose specified.

3. The combination, with a burner, of a conduit leading thereto, a valve in said conduit, a lever connected to said valve at one end, a

thermostatic rod connected to said lever at the 20 other end by an adjustable connection, and an offset-support for said rod, substantially as specified.

4. The combination with a burner, a conduit leading thereto, a valve in said conduit, 25 a mantle surrounding said burner, a thermostatic rod arranged adjacent to said burner and connected to said valve, and a support for said rod, said support being farther removed from the influence of the heat of said 30 burner than said thermostatic rod, substantially as specified.

In testimony whereof I have hereunto set my hand this 24th day of March, A. D. 1905.

DON HENRY KENT.
